Primary Examiner — Melanie H Tung

CLAIM

The ornamental design of a display screen or portion thereof with graphical user interface, as shown and described.

DESCRIPTION

FIG. 1 is a front view of a display screen or portion thereof with graphical user interface, showing our new design; and, FIG. 2 is an enlarged front view taken from FIG. 1. The broken line showing of a watchband and bezel in FIG. 1 shows environment and forms no part of the claimed design. The dot-dash broken line around the graphical user interface shows a display screen or portion thereof and forms no part of the claimed design. The broken line showing of the characters and text forms no part of the claimed design.

1 Claim, 2 Drawing Sheets
